(57) **CLAIM**

The ornamental design for animated display, as shown and described.

DESCRIPTION

FIG. 1 is a perspective view of a first embodiment of an animated display with an environmental feature of one exemplary type of figure.

FIG. 2 shows a front elevation view of the animated display of FIG. 1.

FIG. 3 shows a top plan view of the animated display of FIG. 1.

FIG. 4 shows a side elevation view of the animated display of FIG. 1.

FIG. 5 shows a perspective view of a back side of the animated display of FIG. 1.

FIG. 6 shows an exemplary configuration of the animated display of FIG. 1 wherein the exemplary figure is located in an alternate position.

FIG. 7 shows an exemplary configuration of the animated display of FIG. 1 wherein the exemplary figure is located in another alternate position.

FIG. 8 is a perspective view of a second embodiment of an animated display with one exemplary type of figure.

FIG. 9 shows a front elevation view of the animated display of FIG. 8.

FIG. 10 shows a top plan view of the animated display of FIG. 8.

FIG. 11 shows a side elevation view of the animated display of FIG. 8; and,

FIG. 12 shows a perspective view of a back side of the animated display of FIG. 8.

The broken lines in the drawings depict environmental structure only and form no part of the claimed design.
